UNITED STATES PATENT OFFICE.

JESSIE SMITH ORNES AND LULU VERHOREN LAVELL, OF MINNEAPOLIS, MINNESOTA.

DESIGN FOR A MANTEL CLAMP.

Application filed March 16, 1928. Serial No. 25,884. Term of patent 14 years.

To all whom it may concern:

Be it known that we, JESSIE SMITH ORNES and LULU VERHOREN LAVELL, citizens of the United States, residing at Minneapolis, in the county of Hennepin and State of Minnesota, have invented a new, original, and ornamental Design for Mantel Clamps, of which the following is a specification, reference being had to the accompanying drawing, forming part thereof.

The figure is a perspective view of a mantel clamp showing our new design.

We claim:

The ornamental design for a mantel clamp as shown.

JESSIE SMITH ORNES.
LULU VERHOREN LAVELL.
